No. 738,378.

PATENTED SEPT. 8, 1903.

J. R. VAN DANIKER.
EMERGENCY AUTOMATIC AIR TRAIN STOP.
APPLICATION FILED MAR. 12, 1903.

NO MODEL.

UNITED STATES PATENT OFFICE.

JOSEPH R. VAN DANIKER, OF PHILIPSBURG, PENNSYLVANIA.

EMERGENCY AUTOMATIC AIR TRAIN-STOP.

SPECIFICATION forming part of Letters Patent No. 738,378, dated September 8, 1903.

Application filed March 12, 1903. Serial No. 147,507. (No model.)

To all whom it may concern:

Be it known that I, JOSEPH R. VAN DANIKER, a citizen of the United States, residing at Philipsburg, in the county of Center and 5 State of Pennsylvania, have invented certain new and useful Improvements in Emergency Automatic Air Train-Stops, of which the following is a specification.

The stoppage of railroad-trains where the engineer fails to notice and to act upon the danger-signals is the object of my invention; and for this purpose I have designed an automatic emergency stop mechanism adapted to be operated with the usual signals and semaphores at block-stations and elsewhere along 15 the track to release the pressure in the main air train - pipe to instantly set the brakes whenever a train is passing or has passed through the signals, and thereby bring the 20 train to a stop.

The accompanying drawings illustrate my improved emergency automatic air train-stop, and in the claims appended hereto I will point out the parts and combinations of parts which 25 constitute my improvement.

Referring to the drawings, Figure 1 shows in side view so much of a locomotive-engine as illustrates the use of my invention. Fig. 2 is a view looking at the front of the locomotive, showing my emergency train - stop mechanism as applied for use at both rails of 30 the track, the trip devices being located outside of the rails. Fig. 3 is a view showing the tripping device located at the inner side of 35 the rail. Fig. 4 is an enlarged sectional view showing the track valve opening or tripping device and the rod connecting it with the signal-station, whereby the slidable stop or trip device is vertically raised in the path of the 40 train air-brake valve in the event of an emergency for its use. Fig. 5 is a detail showing the slidable valve-opening device and the connections for vertically moving it in and out of the path of the moving-train valve. 45 Fig. 6 is a vertical section of the emergency-valve in its closed position, and Fig. 7 is a horizontal section of the same.

It will be understood that my emergency air train-stop may be applied to and rendered 50 operative at both rails of the track and in either direction of the run of the train, and looking at Fig. 2 a part of the main train air-

pipe 1 is seen having a branch 2, depending from the frame at each side of the locomotive and each branch provided with an emergency-valve adapted to be operated by the vertically-slidable track valve opener or trip, both the emergency-valve and its trip or opener having a novel construction and coöperating to bring the train to a standstill. The emergency-valves shown in Figs. 6 and 7 each consists of a case or shell 3, circular in cross-section and having opposite side ports 4 4 and an end nippled opening 5, with which the branch air-pipe 2 connects, and a plug 6, ground to fit 55 the inner walls of the shell, having a central port 7 in perpetual communication with the air-pipe 2, and radial ports 8 8, intersecting the central port and adapted to register with the shell-ports 4 4 when the plug is turned in 60 its shell. The lower end of the shell has a central opening through which a stem 9 of the plug projects and terminates in horizontal arms 10, whereby the valve-plug is turned to open the air-pipe in a way which I will presently state. From this construction it will be 65 seen that the emergency-valve is suspended by the train air-pipe, so that its stem hangs centrally from the valve-case with its horizontal arms 10 standing across the rail, as in Figs. 70 80 and 3.

The valve opener or trip is a track appliance and consists of a tubular part, preferably formed like an inverted cup 11, forming a cap or cover to a pedestal 12, which is held low and is firmly secured upon a cross-tie. 85 A rod 13, rigid with and depending centrally from the cap, passes through the pedestal, and a lever 14, preferably of bell-crank form, pivotally mounted in the tie, connects this 90 cap-rod with a rod 15, which extends to the block-signal station where it is provided with suitable operating connections (not shown) for raising and lowering the cap or trip. For this purpose the open end of the cap telescopes with the open top of the pedestal, an inward-standing lip of the cap and an outward-standing lip of the pedestal serving by their engagement to limit the upward slid- 95 able movement of the cap to render it secure 100 and to protect the working connections of the cap or trip from rain and snow. The cap-operating rod is housed in a tube 16 and rests therein on balls 17 to render easy the move-

ment of the rod in pulling it at the signal-sta-
tion to slidably raise the cap or trip in posi-
tion to be struck by the valve-arm 10, as seen
in Figs. 2 and 3, to turn and open the valve,
5 or in pushing the rod to lower the cap to its
normal position, as seen in Fig. 1 and in dotted
lines in Fig. 4, to place it out of the path of
the valve-arms, so that the air-valves will not
be actuated by the passing train.

10 To render certain the lowering of the caps
or trips to their normal positions, a spiral
spring 18, Fig. 4, is connected to the under
side of the closed end of the cap and to the
inner wall of the pedestal to constantly tend
15 to pull the cap or trip downward, and it will
be understood that the pilot will at all times
pass free of the caps. The caps or trips for
opening or turning the valves may be fixed
along the inner or the outer sides of the rails,
20 and I prefer to arrange them at each rail and
connect them in pairs by a suitably-housed
cross-rod 19, which forms the pivot-mounting
for the cap-operating bell-crank levers, so that
the caps are slidably raised and lowered in
25 pairs simultaneously, and the train air-valves
are preferably arranged in pairs one at each
side of the train to be opened simultaneously
by the train-trips. This renders it certain
30 that the arms of one or both valves will strike
the cap and be moved by it, and thereby cause
the arm to turn the valve-plug in its shell,
putting the valve-ports in communication
instantly applying the brakes. The length
35 of the arms is such that they will pass the
caps after turning the valves, and it will be
understood that the caps are arranged at suit-
able places and distances apart along the
track. The air-valves may have arms pro-
40 jecting beyond the inner and the outer sides of
the rail, so that these valves may be equipped
for caps located on either side of the rail,
and it will be understood that the normal po-
sitions of the arms of the valve-plugs are at
45 right angles to the rails and that the valve-
plugs are closed, as in Fig. 6, and that when
the plug-valve is turned to open its ports to
the air, as shown by dotted lines in Fig. 7,
such turning of the plug is limited to regis-
50 ter the valve and its shell-ports by pins 20,
depending from the shell and against which
the valve-arms strike when turned by the cap.
In this position of the arms the plug-valve re-
 mains open and is subsequently closed by the
55 engineer; but the way in which the plug-valve
is seated and housed will keep it closed until
struck by the cap or trip. By this construc-
tion of stop mechanism the train may be
stopped, whether going forward or backward,
60 and it is obvious that the air-valves may be
used on one side of the train only and be op-
erated by trips along one of the rails only.
It is also obvious that the vertically-slidable
65 caps or trips may be used in harmony with
the semaphore or independently of the sema-
phore and that the trip may be actuated me-

chanically by fluid-pressure or electrically.
It is important to note that the cap or trip is
always supported in a vertical position, is
slidable in a vertical line only, and is firmly
70 braced by the pedestal on which it slides, and
that the connections by which it is raised and
lowered are not subjected to the force of the
impact of the valve-arm against the trip by
the moving train. It is also important to note
75 that the arrangement of the vertically-slid-
able trips in connected pairs one at the side
of each rail is advantageous in effecting the
simultaneous elevation of the valve-trips by
the connection only of one of the trips with
80 the actuating-rod extending to the signal-sta-
tion.

I claim—

1. In an emergency train-stop, the combina-
tion of a valve controlling the air-brake pipe
85 and having a laterally-extending arm, a trip
located at the side of the rail and comprising
telescoping members, mechanical means con-
nected with the upper member to elevate it
into the path of the valve-arm, and means for
90 retracting said upper member.

2. In an emergency train-stop, the combina-
tion of a valve controlling the air-brake pipe
95 and having a laterally-extending arm, a trip
located at the side of the rail and comprised
of a lower tubular fixed member and an upper
tubular member telescoping with and slidable
on the lower member, mechanical means for
elevating the upper member into the path of
the valve-arm, and a spring for retracting the
100 upper member.

3. In an emergency train-stop, the combina-
tion of a valve carried by the air-brake pipe
105 and provided with a horizontal arm, a verti-
cally-slidable tubular trip or cap located at
the side of the rail, a fixed pedestal on which
the trip is slidably mounted and forms a tele-
scoping cover a rod centrally fixed to the cap
or trip within the pedestal, a lever pivoted
at the base of said pedestal and pivotally
110 connected to the trip-rod and a rod connected
to said lever and extending to the signal-sta-
tion.

4. In an emergency train-stop, and in com-
bination, a valve carried by the air-brake 115
pipe at each side of the train each valve pro-
vided with a horizontal arm, a pair of verti-
cally-slidable trips or caps one at the side of
each rail, and means connecting one of the
pair of trips extending to the signal-station,
120 whereby both pair of stops are simultaneously
actuated in the way stated to cause the brakes
to be applied.

5. In an emergency train-stop, and in com-
bination, a valve carried by the air-brake 125
pipe at each side of the train each valve pro-
vided with a horizontal arm, a pair of verti-
cally-slidable trips or caps, one at each side of
the rail, a fixed pedestal for each trip or cap,
a rod centrally fixed to the trip or cap within
130 the pedestal, a lever device pivotally connect-
ed to each trip-rod, a rod crossing the track

and carrying said levers, and a rod connected to one of said levers and extending to the signal-station.

6. In a train-stop, and in combination with the air-brake pipe, an emergency-valve carried by said pipe consisting of a case or shell having ports, a plug-valve having a port in perpetual communication with the air-pipe, and ports adapted to register with the shell-ports and having a central stem projecting downward through the shell, and terminating in a horizontal arm, a vertically-slidable trip or cap located at the side of the rail, means for elevating the trip in the path of the valve-arm whereby the arm in striking the trip is caused to be turned to vent the air-pipe, and stops on the shell for limiting the turning of the valve.

7. In an emergency-brake, and in combination, a valve carried by the air-brake pipe 20 and provided with an arm, a vertically-slidable cap or trip located at the side of the rail and adapted to be elevated into the path of the valve-arm, a fixed support on which the cap is slidably mounted, a rod and a lever connecting the cap and the pedestal, a spring connecting the cap or trip and the pedestal constantly tending to pull the trip down, and a rod connected to the lever and extending to the signal-station. 25 30

In testimony whereof I affix my signature in presence of two witnesses.

JOSEPH R. VAN DANIKER.
